UNITED STATES PATENT OFFICE.

JOSEPH EDMONDSON AND JOSEPH OULTON, OF BRADFORD, ENGLAND.

ELECTRIC METER.

SPECIFICATION forming part of Letters Patent No. 496,728, dated May 2, 1893.

Application filed September 29, 1892. Serial No. 447,288. (No model.)

To all whom it may concern:

Be it known that we, JOSEPH EDMONDSON and JOSEPH OULTON, subjects of Her Majesty the Queen of Great Britain, residing at Bradford, in the county of York, England, have invented certain new and useful Improvements in Electricity-Meters, of which the following is a specification.

This invention relates to improvements in 10 electricity meters in which the vibrations of a chronometric balance or balances, pendulum or pendulums in combination with magnets or solenoids are made to record the amount of electric current or energy passing 15 into consumption, and consists in the use of a pendulum or pendulums each driven by an arm actuated by gravity or by a spring such for instance as the gravity arms in the well known "Beckett's gravity escapement" but 20 lifted in our improved manner by electromagnetic force instead of by clockwork driven by a spring or weight.

In the case of a chronometric balance the impulse arm is actuated by a spring. It also 25 consists in combining a resistance with a condenser and the electric circuit of the electro-magnet, so as to lessen or prevent sparking at the point where the pendulum or balance opens, or closes the said circuit. It also deals 30 with apparatus for stopping the said pendulums or balances when the electric current is intermittent and also for re-starting the said pendulums, or balances when the current is again switched on such with electricity meters 35 in which two pendulums or chronometric balances are employed, such pendulums or balances being required to beat synchronously when no current is passing into consumption. In order the more effectually to insure such 40 synchronism we attach the two pendulums to a bar which is common to both of them and which is itself held by a more or less elastic support. In the case of two chronometric balances we suspend these from more or less 45 elastic supports which are connected together by a rod or bar by which the vibrations are more or less communicated from the one to the other. Such being the nature and object of our invention the following is a complete 50 description of same, in the case where two pendulums or chronometric balances are used, reference being made to the accompanying

drawings in which similar letters of reference point to the same or similar parts throughout.

Figure 1 is a front elevation of the pendulum form of our improved electrical meter or apparatus for measuring and indicating the amount of electric current or energy passing into consumption such apparatus being electrically connected with a train of wheels and 55 dials such as illustrated by Figs. 4, 5 and 6. Fig. 2 is a detail of part of Fig. 1 drawn to an enlarged scale in order to show its construction more clearly. Fig. 2^A is a similar view to Fig. 2 but showing the action of the magnet and weight reversed. Fig. 3 is an end sectional elevation on line A B of Fig. 1. Fig. 4 is a front elevation of the indicating dials. Fig. 5 is a plan view of Fig. 4 showing the train of wheels for operating the hands of the 60 dials. Fig. 6 is a detail of part of the indicating mechanism drawn detached in order to show its construction more clearly. Fig. 7 is a front elevation of a part of Fig. 1, drawn detached and with the pendulum rod removed 65 in order more clearly to illustrate part of the invention. Fig. 8 is an end view of Fig. 7 the pendulum rod being in position. Fig. 9 is a plan view of Figs. 7 and 8 showing the apparatus connected with a condenser. Fig. 10 is 70 a similar view to Fig. 9 but showing a resistance coil connected to and combined with the apparatus and the condenser. Fig. 11 is a front elevation of the apparatus as constructed when chronometric balances are employed 75 in lieu of the pendulums. Fig. 12 is an end view of a part of Fig. 11. Fig. 13 is a plan view of part of Fig. 11 the position of the chronometric balance being indicated by the dotted lines. Fig. 13^A is a detail of Fig. 13 80 drawn to an enlarged scale in order to show its construction more clearly. Fig. 14 is a similar view to Fig. 13, without the trapping motion, which may be dispensed with in some cases.

Referring first to meters in which pendulums are employed and to Figs. 1, 2 and 3 of the accompanying drawings, at 1-1 are two pendulums whereof one is an ordinary pendulum which may be conveniently regulated by 85 a screw 33 as shown and the other is a pendulum influenced by the current to be measured in any convenient manner. We prefer 90 the method shown in the drawings which con-

sists of a fixed main coil 58 together with the volt or high resistance coil and a correcting coil on the pendulum as hereinafter described and marked 65. The pendulums are 5 made to vibrate the required motion being maintained by gravity impulse arms 2—2 said arms 2—2 being mounted on axes free to move in the carrying frames or brackets 3—3 (see Figs. 7, 8, 9). Mounted loosely in the said 10 brackets 3—3 and below each of the arms 2—2 is an armature 4 one end of which is near to the electro magnet 5 and the other end is provided with a counterbalance weight 6.

On each pendulum rod 7 is a short cranked 15 finger 8 (see Fig. 2) at the outer end of which is an adjusting screw 9 and also a small blade spring 10 fixed at one end by a screw or otherwise on the said cranked finger 8. The free end of the spring 10 rests on the adjusting 20 screw 9. On the upper side of the spring 10 is a small projection, or a piece of platinum 11 which as the pendulum vibrates, comes into contact with a similar projection 12 on the impulse arm 2. A screw 13 (Figs. 7, 8 and 9) 25 limits the amount of movement of the armature 4.

The action is as follows:—In a state of rest or in the normal position the counterbalance weight 6 holds the armature 4 in contact with 30 the screw 13 and away from the electro magnet 5 the gravity arm resting on the top side of the armature 4. As the pendulum vibrates and moves to nearly the limit of its arc in one direction the projection or platinum 11 35 of the spring on the cranked finger 8 will come in contact with the projection or platinum 12 on the impulse arm 2. At the moment of contact and while the pendulum moves through its supplementary arc (the 40 circuit being closed as hereinafter described when referring to the different coils and their connections) the armature 4 is attracted to the electro magnet 5. When the pendulum moves in a reverse direction the gravity impulse 45 arm 2 falls with it until the arm rests upon the armature 4. The circuit is then opened by the part 11 moving away from the part 12 and the armature leaves the magnet and lifts the gravity arm to its original position. It 50 will be seen that the impulse arm falls through a longer arc than that through which it is raised by the vibration of the pendulum the difference being the height to which the impulse arm is raised by the armature 4. The 55 repeated fall of the impulse arm 2 through this short distance is sufficient to maintain the vibrations of the pendulum. The impulse arm may be actuated by a spring instead of by gravity. It will be evident that 60 the action of the magnet 5 and weight 6 may be reversed as shown in Fig. 2^A. In this case the impulse arm 2 is mounted in bushes which insulate it from the frame 3 its arbor being electrically connected to the bar 30 by a light 65 flexible connection. When the impulse arm 2 rests on the top of the weight 6 the electric circuit of the magnet 5 is completed the ar-

mature 4 is consequently drawn down and the impulse arm 2 is lifted along with the weight 6. When the pendulum moves in the direction of the arrow and lifts the impulse arm 2 by means of the screw 9 the circuit is broken at 11—12, the magnet 5 releases the armature 4 and the weight 6 falls as far as permitted by the stop 13. When the pendulum moves 75 in the reverse direction the arm 2 falls with it until the arm rests again on the weight 6 completes the circuit and the magnet 5 again lifts the weight 6 and arm 2 to the first named position. 80

In order to lessen or prevent sparking at the points of contact 11—12 whenever the electric circuit is opened or closed, we combine an ordinary condenser such as 14 and a resistance coil such as 17 with the electric circuit of the electro magnet 5 a wire 15 from the frame 3 being connected with one side of the condenser, and a wire 16 connecting the opposite side of the condenser 14 and the resistance 17 (see Figs. 1 and 10.) 90

The improved apparatus for stopping the pendulums 1—1 when the current is intermittent, and for restarting the said pendulums when the current is switched on, consists of an electro magnet 18 near the bottom of 95 which is hinged an armature 19 the outer ends of which are cranked as at 20 and the cranked ends 20—20 pass underneath the two arms 21—21 which latter rest on the cranked ends 20—20. The arms 21—21 are 100 at their inner ends hinged, or free to move on fulcrum pins 22—22 and their outer ends carry the pins 23—23. A hook 24 is fixed on the rod 7 of each of the pendulums 1—1 in such a position as to engage with the pins 105 23—23 when these are in their lowest position. When current is passing through the circuit of the electro magnet 18 the said magnet holds up the armature 19 which then supports the arms 21—21 in a position too high 110 for the hooks 24—24 to engage with the pins 23—23. But when the current is switched off the armature 19 falls and allows the arms 21—21 to fall by gravity to their lowest position. When this is so (as the pendulums 1—1 115 vibrate toward one another) the inclined edges 25 of the hooks 24 will come in contact with and move underneath the pins 23—23 until the latter fall into the catches 26—26 of such hooks. The pendulums 1—1 are thus 120 stopped and will be held stationary at an elevation above their dead point. As soon as the electric current is again switched on, the electro magnet 18 will draw to it the armature 19 and the cranked ends 20—20 will raise 125 on their centers the arms 21—21 and pins 23—23 and, as the latter move up the inclined faces of the catches 26—26 with a sharp movement, the pendulums 1—1 receive a slight impulse toward each other the hooks 24 are released from the pins 23 and the pendulums 130 resume their vibrations. The lifting action of the magnet 18 is made more certain by a larger current temporarily passing through

the circuit of the magnet by way of the hooks 24—24 pins 23—23 and arms 21—21 as herein-after described.

In order that the synchronism of the two pendulums 1—1 may be effectually maintained when no current is passing into consumption we attach the two pendulums 1—1 by the usual suspension springs 27—27 to a bar 28 common to both pendulums and this bar 28 is itself supported by springs 29—29 (or other elastic support or supports) which are attached to a bar 30 secured to the box or casing of the meter. Passing through a slot or hole in the bar 28 is a screwed pin 31 fixed in the bar 30 and nuts 32 are placed on each side of the bar 28 so that the latter can be held rigid or nearly so by causing the nuts 32 to nip it between them. This bar 28 being thus made rigid or nearly so the pendulums 1—1 are made to vibrate synchronously by the regulating weight 33 which is screwed up or down on the pendulum rod as required. The bar 28 is then released from the grip of the nuts 32—32 and the synchronism is maintained by the vibration of the one pendulum being able to slightly influence those of the other. The screwed pin 31 and the nuts 32—32 may be dispensed with, but in this case the primary adjustment of the pendulums for synchronism will not be so accurate. When in lieu of the pendulums 1—1 we employ chronometric balances 1—1 (see Figs. 11 and 13) the said balances 1—1 being made to vibrate, their motion is maintained by the impulse arms 2—2 which are mounted on axes 35 free to move in the carrying frames or brackets 3—3. On the axis 35 is a vibrating spring 34 (preferably similar to the balance spring of a watch). Mounted loosely in the brackets 3—3 is an armature 4 one end of which is near to the electro magnet 5 but held (when no current is passing round such magnet) against the adjusting screw 13 by the spring 6. It is shown in the drawings Fig. 13 as attracted by the magnet, and away from the said adjusting screw 13. On each balance 1 is a pin 11 which as the balance vibrates, comes in contact with the end 12 of the impulse arm 2.

The action is as follows: In a state of rest, or in the normal position, the spring 6 holds the armature 4 against the adjusting screw 13 and away from the electro magnet 5. The impulse arm 2 then rests against the armature 4 being retained there by the force of the spring 34. As the balance vibrates, and moves to nearly the limit of its arc in the direction of the arrow the pin 11 will come in contact with the end 12 of the impulse arm 2.

The balance continues its motion through its supplementary arc (the circuit being closed as hereinafter described when referring to the coils and their connections) the armature 4 is attracted to and held by the electro magnet 5. When the balance moves in the reverse direction the impulse arm 2 is made by the spring 34 to follow it until it comes in contact

with the armature 4 the pin 11 then leaves it behind, the circuit is broken and the armature 4 being released the spring 6 brings it 70

back to the stop 13 and carries the impulse arm 2 with it. It will be seen that the impulse arm 2 moves through a shorter arc when carried by the balance in the direction of the arrow than when it returns with it, the difference being the distance between the position of the armature 4 when it is against the magnet and its position when against the adjusting screw 13. This difference gives the required impulse to the balance. 80

The apparatus employed for stopping, and restarting the balances 1—1 is similar to that described with reference to Figs. 1 and 3 excepting that the pin 23 is fixed to and at about the center of gyration of the radius of the balance 1 and the springs 36 (see Fig. 13) are employed to keep the arms 21—21 in contact with the cranked ends of the armature 19. The arms 21—21 terminate in the hooks 24—24. As long as the current is passing round the magnet 18 the armature is held by it and the arms 21—21 are held with their hooks 24—24 out of reach of the pin 23 but when the current is switched off the armature 19 is released and the hooks 24—24 are by the springs 95 36 brought within range of the pins 23 which they catch and so hold the balances in a position away from their neutral or dead point, until the hooks are withdrawn by the renewed action of the current. 100

In order that the synchronism of the balances 1—1 may effectually be maintained when no current is passing into consumption we attach the two balances 1—1 by the usual torsion suspension springs 27—27 (Figs. 11 and 12) which are supported by the much stronger springs 29—29 or other somewhat elastic support or supports attached to a bar 30 secured to the box or casing of the meter. The elastic supports 29—29 are connected to one another by the bar 28 the supports 29—29 being bent or having a crank formed on them, and these cranks 37 are received in the recesses 38 formed one at each end of the bar 28 and held by means of the small springs 39—39 their ends resting in the notches 40—40 of the recesses 38—38. The action, and result of suspending the balances 1. 1. as described is similar to that hereinbefore described in reference to Figs. 1 and 3. 110 115 120

The index which records the amount of electric current or energy passing into consumption to which we make no separate claim consists of the dials and hands (see Figs. 4 and 5) the hands being actuated by the train of wheels (see Fig. 5) such train of wheels being operated and operating as follows. The electric circuits of the two electro-magnets 41—41 are connected in series with the electric circuits of the magnets which actuate the impulse arms (one to each) and near to each magnet 41 is an axis 42 (seen most clearly in Fig. 6) on which is fixed the armature 43 and also the lever 44, the upper end of which has 125 130

two cross arms 45—45 in which are pins 46—46 carrying the blade springs 47—47 which engage with the teeth of a ratchet or catch wheel 48 carried on an arbor 49 which passes through the slot 50 in the lever 44. On the arbor 49 is a pinion 51 gearing with and driving the wheel 52 of the differential motion 53 and on the arbor 49^A is the pinion 51^A gearing with and driving the wheel 52^A of the differential motion. When current passes around the electro magnets 41—41 (in consequence of the circuits being closed at the contacts 11 and 12 by the vibration of the respective pendulums or balances) the armatures 43—43 are attracted to such magnets 41—41 consequently the axes 42—42 are turned part of a revolution and the levers 44—44 are moved in the direction indicated by the arrows in Fig. 6 the ends of the upper blade springs 47—47 come in contact with the teeth of the ratchet or catch wheels 48—48 and the latter are turned a space of half a tooth. When the circuit is again opened the spiral springs 54—54 move the levers 44—44 in a reverse direction to that indicated by the arrows in Fig. 6 and the lower blade springs 47—47 now move the ratchet or catch wheels 48—48 a space of half a tooth in the same direction as before. This to and fro movement of the levers 30 is repeated so often as the circuit is open and closed by the pendulums or balances consequently the pinion 51 rotates and drives the wheel 52 in a reverse direction to that in which the pinion 51^A drives the wheel 52^A. So long as the speed of these wheels 52, 52^A is the same the wheel 55 will remain stationary. When the speed of the wheel 52 varies from the speed of the wheel 52^A in consequence of the deviation from synchronism of the pendulums or 40 balances caused by current going into consumption the wheel 55 will rotate and set in motion the train of wheels or clockwork which drives the hands or indices. The stop pins 56—56 on the levers 44—44 prevent the ratchet or catch wheels 48—48 moving more than the distance or space of half a tooth at one time or for one vibration of the levers 44—44. The electro magnets in this invention may be either with or without iron cores and their 50 armatures may be either of iron or of a coil or coils placed in a shunt circuit and with or without iron cores.

Although we have here described the application of electrically actuated impulse arms on two pendulums or balances of electric meters where the basis of measurement is the amount of variation from synchronism of the said pendulums or balances, it will be readily understood that the same method of driving 55 may be applied in electricity meters in which only a single pendulum or balance is used, to which construction our invention equally applies.

We will now describe how the different 60 parts of the apparatus are connected together, and indicate the flow of the electric current through the meter. At 57 (see Fig. 1) is the

+ main supply wire along which the current passes around the fixed main coil 58 to the lamps. The wire 57 is connected by shunt 70 wire 59 with the bar 30 through which a current for actuating the movements and index passes down the springs 29—29 and pendulum rods 7—7 and (when contact is made between the parts 11—12) along the impulse 75 arm 2 to the frame 3 which is connected (as shown in Fig. 10) by the wire 15 to the resistance 17 thence by wire 15 to one side of the condenser 14 the opposite side of the condenser being connected by the wire 16 to the 80 bar 30 or the reverse as shown in Fig. 1. We prefer inductive resistances as shown in the drawings and one of them may be placed on each side of the condenser 14 if desired or thought necessary. The circuit is continued 85 from the frame 3 by wire 60 round the magnets 5—5 and by wire 61 to the index. Another current passes along the pendulum rod to the fork 63 thence by wire 64 to correcting and volt coils 65 which are upon and form 90 part of the pendulum or balance and whose functions are hereinafter described. From the correcting coil 65 the current passes up the pendulum rod 7 by the wire 66 away to the main wire for supplying the lamps. A 95 wire 67 from the volt coil 65 also passes along the pendulum rod to the frame 3^A of the electro magnet 18 and the current flows by wire 68 to said electro magnet and thence by wire 69 to the supply terminal. The wires 66—67 10 may be carried inside the pendulum rod 7 the latter being made hollow for this purpose. When the hooks 24—24 are engaged with the pins 23—23 of the arms 21—21 a short circuit is formed between the pendulum rod 7 through such hooks 24 pins 23 arms 21 and frame 3^A to the electro magnet 18 thence to the supply terminal. The volt coil 65 being thus temporarily cut out the magnet 18 is much more powerful, and when the current 11 is switched on the armature 19 is strongly attracted and moves sharply to the magnet 18. The connections are similar when torsion balances are employed excepting that wires 70—70 are employed dipping into the 11 mercury cups 71—71 by way of which the current passes as indicated in Fig. 11. It will be seen that instead of the current to the magnet 18 being passed through the volt coil, when the pendulums are vibrating it 12 might equally well be passed instead thereof through a separate coil of similar resistance coupled between the frame 3^A and the main wire 57, or further instead of the contact between the hooks 24 and the pins 23 cutting out the said separate resistance coil or the volt coil, the said contact might close the circuit of a second coil placed on the core of the magnet 18 by which the magnetism would be temporarily increased as required. 13 A very small current is continually passing through the shunt circuit which includes the volt coil 65, the magnetic effect of which is in proportion to the electro-motive force of the

current. When current is passing through the fixed main coil to the lamps, the magnetic force of the main coil and of the volt coil combined, accelerate or retard the vibrations of the pendulum such acceleration or retardation being registered on the dials and being, except as hereinafter described in proportion to the watts passing into consumption. The force required to produce the vibrations of a pendulum is in proportion to the square of the number of vibrations. If therefore a equals the normal number of vibrations and b equals the number to be added by the current the force required to produce a will be a_2 and to produce $a+b$ will be $a_2+2ab+b_2$, the difference $(2ab+b_2)$ being the force to be exerted by the current under measurement. With the volt coil alone the force actually exerted would be in the ratio $2ab+b_2$ only. Upon each volt coil therefore there is wound the "correcting coil" carrying a very small proportion of the current passing into consumption. If correctly calibrated this small current brings the ratio up to $2ab+b_2$ and makes the readings proportional throughout any range.

In the following claims we have used the term "vibrating contact maker" as broadly defining the hereinbefore described pendulums and chronometric balances, or their equivalents, and we wish to be so understood.

What we claim is—

1. In an electric meter, the combination with a vibrating contact maker of an impulse arm adapted to impel the said contact maker, an electro magnet, and an armature for the said magnet adapted to lift the said impulse arm, substantially as described.

2. In an electric meter, the combination with a magnet, of a vibrating contact maker, an impulse arm lifted thereby through a part of its movement and making contact therewith, the said contact maker and impulse arm being in circuit with the said magnet, and an armature for the said magnet lifting the said impulse arm through the remainder of its path, substantially as described.

3. In an electric meter, the combination with a vibrating contact maker having a hook thereon, of a coil mounted on the said contact maker, a fixed electro magnet an electric circuit including the said magnet and hook, a second electric circuit including the said magnet and coil, an armature for the said magnet, and a lever actuated by the said armature and adapted to engage the said hooks, and to cut out the said coil and to short circuit the first named circuit through the said magnet, substantially as described.

4. In an electric meter, the combination with a plurality of vibrating contact makers, of a flexibly suspended bar carrying the contact makers, whereby the vibrations of each contact maker slightly influences those of the others, substantially as described.

5. In an electric meter, the combination with a magnet, of a vibrating contact maker,

an impulse arm lifted through a part of its movement thereby and making contact therewith, the said contact maker and impulse arm being in circuit with the said magnet, an armature for the said magnet adapted to lift the said impulse arm through the remainder of its path and a condenser placed in a parallel circuit of suitable resistance to the said magnet, contact maker, and impulse arm, substantially as described.

6. In an electric meter, the combination with a vibrating contact maker having a hook thereon, of an impulse arm adapted to impel the said contact maker, an electro-magnet arranged in circuit with the said contact maker, and impulse arm, an armature for the said magnet adapted to lift the said impulse arm, a second electro-magnet, and an armature therefor, and a lever actuated by the last named armature adapted to engage the hook upon the said contact maker, substantially as described.

7. In an electric meter, the combination with a vibrating contact maker having a hook thereon, of a coil carried on the said contact maker, a fixed magnet, an electric circuit having included therein the said magnet and coil, an armature for the said magnet, and a lever actuated by the said armature and adapted to engage the hook upon the said contact maker, substantially as described.

8. In an electric meter, the combination with a vibrating contact maker, of an impulse arm adapted to impel the said contact maker and to make contact therewith, an electro-magnet arranged in circuit with the said contact maker and impulse arm, and an armature for the said magnet adapted to lift the said impulse arm, and to release it upon the completion of the circuit between the said impulse arm and the vibrating contact maker, substantially as described.

9. In an electric meter, the combination with a vibrating contact maker, of an impulse arm adapted to impel the said contact maker and make contact therewith, an electro magnet in circuit with the said contact maker and impulse arm, and an armature therefor adapted to lift the said impulse arm, substantially as described.

10. In an electric meter, the combination with a vibrating contact maker having a hook thereon, of a coil carried by the said contact maker, a fixed electro-magnet, an electric circuit including the said hook, coil and electro magnet, an armature for the said magnet and a lever actuated by the said armature and adapted to engage the said hook and electrically connected with the said magnet, whereby the said coil will be short circuited, substantially as described.

11. In an electric meter, the combination with a vibrating contact maker of an impulse arm adapted to impel the said contact maker and make contact therewith, two electro-magnets included in circuit with the said contact maker and impulse arm, a clockwork driven

by one of the said magnets and an armature for the other magnet adapted to raise the said impulse arm, substantially as described.

12. In an electric meter, the combination with a vibrating contact maker having a hook therein of an impulse arm adapted to impel and make contact with the said vibrating contact maker, two magnets arranged in circuit with the said contact maker and impulse arm, a 10 clockwork driven by one of the said magnets, an armature for the other magnet adapted to lift the said impulse arm, an electro magnet

and armature, and a lever actuated thereby and adapted when at rest to engage the hook upon the contact maker, substantially as described. 15

In testimony whereof we have hereunto set our hands in the presence of two subscribing witnesses.

JOSEPH EDMONDSON.
